LOOM ATTACHMENT

Filed Jan. 22, 1929

UNITED STATES PATENT OFFICE

CLIFFORD HARGREAVES, OF DRUMMONDVILLE, QUEBEC, CANADA, ASSIGNOR TO
CELANESE CORPORATION OF AMERICA, A CORPORATION OF DELAWARE

LOOM ATTACHMENT

Application filed January 22, 1929. Serial No. 334,184.

This invention relates to an improvement in looms, and particularly dobby looms, wherein the number of bars in the pattern chain may be materially reduced when fabrics having a weft of different kinds of yarns are to be woven.

An object of my invention is to provide an attachment for looms, whereby the number of bars on the pattern chain of the loom may be materially reduced.

Another object of my invention is to provide an auxiliary cylinder in a dobby loom, which cylinder actuates the shuttle changing mechanism, and which in turn is controlled by the pattern chain of the main dobby cylinder. Other objects of my invention will appear from the following detailed description.

In the ordinary dobby attachment in a loom, a pattern chain is provided, which chain has a series of bars having pegs for controlling the raising and lowering of the shafts of the harness for producing the desired shed of the warp. In those cases where a change of the nature of the filling or weft is required, which change may be a change of color or a change of nature of the yarn, for making borders, check designs, stripes and the like, pegs are inserted in the bars of the chain, in order to control the change of the weft shuttle to effect change of the weft. The number of links or bars required for this purpose is often very large, since sufficient links must be provided to weave the entire pattern until a repeat of design is reached. Thus, if a check design of simple weave is to be woven, wherein 50 white picks and 50 colored picks are required, if each link controls two picks, a chain of 50 bars is required in order to effect the required change in the weft, despite the fact that the number of bars required for actuating the shafts of the harness to obtain the desired weave is very small.

In accordance with my invention, an auxiliary cylinder is provided in dobby loom, which auxiliary cylinder is adapted to actuate the mechanism for causing a change in the weft shuttle. This auxiliary cylinder in turn is controlled by pegs, or absence of pegs, on the pattern chain of the main dobby cylinder, so that it may remain stationary for any

desired number of picks. By this means, the number of links or bars in the dobby chain may be materially reduced.

Referring to the drawing, the figure shown therein is a perspective view of my invention shown in connection with that part of a loom that is necessary for an understanding of the same.

On the drawing, 1 indicates the ordinary dobby cylinder that is rotatable and which is provided with the pattern chain made up of pattern bars 2, 2a, 2b, 2c, 2d, etc. These pattern bars have the usual holes therein in which pegs may be inserted in the required places, in order to actuate the dobby fingers 65 and knives in such a manner as to raise and lower the desired shafts of the harness through the action of the griffe bar, in order to obtain the shed of the warp for weaving the desired pattern. At the extreme ends of 70 these pattern links, holes are provided in which pegs are inserted in predetermined links for the purpose to be described. As shown in the drawing, pattern link 2 is provided with a peg 3, the link 2a has no peg, the link 2b has the peg 3a, while of the remaining links, some have pegs and others do not have pegs.

By my invention, I provide an auxiliary cylinder 4 that is mounted for rotation and which is provided with a chain or bars or links, 5, 5a, 5b, etc., which have holes therein at one end in which pegs 6, 6a, etc., may be inserted in certain predetermined bars. As shown in the drawing, the bar 5 is provided 80 with the peg 6, while bars 5a and 5b have no pegs.

The cylinder 4 is provided with a ratchet 7, which is adapted to be engaged by a pawl 8 on the bell crank lever 9, the lower end 10 of which rides on the lever 11 that is pivoted at 11a. This lever 11 is connected by the arm 12 to a lever 13 pivoted at 14, which lever 13 rests either on a peg 3 or on one of the bars of the dobby pattern chain when there is no peg in that bar. The bell crank lever 9 is connected by the link 15 to the arm 16 that carries the ordinary upper and lower griffe bars 17 and 18. These griffe bars 17 and 18 and their connecting bars are caused to re-

ciprocate by means of the arm 180, connecting rod 19 and rotating eccentric 20. It will thus be seen that during the operation of the loom, the bell crank lever 9 is constantly reciprocating because of the reciprocation of the griffe bars, but as long as there is a peg, such as peg 3, on the pattern links 2, 2a, etc., the peg will raise the lever 13, arm 12, lever 11 and thus the pawl 8, so that the pawl does not engage the ratchet 7 of the auxiliary cylinder. However, if a pattern link 2a having no peg is in operative position, the lever 13, arm 12, lever 11 and the pawl 8 will drop so that the pawl 8 engages the ratchet 7, and because of the reciprocating motion imparted thereto by the arm 16, the pawl will cause the auxiliary cylinder 4 to rotate and thus bring a new bar 5, 5a, etc., into operative position.

The pegs 6, 6a, etc., on the bars 5, 5a, etc., of the auxiliary cylinder 4 are adapted to engage the arm 21 of a lever pivoted at 22, which lever has an arm 23 adapted to engage the upper member 25, and a link 24 connected with the lower member 26, of mechanism 27 that is connected by the member 28 with the lever 29 that operates by suitable mechanism (not shown) the shuttle holder changing mechanism. Stops 25a and 26a are provided for limiting the backward motion of the members 25 and 26 respectively, these stops being of the usual character adopted in loom dobby mechanisms.

When there is a peg 6, 6a, etc., on the bar 5, 5a, etc., that is in the operative position, the arm 21 is raised and the members 23 and 24 lowered, thus causing the hooks 30 and 31 to engage the reciprocating upper and lower griffe bars 17 and 18 respectively, and the lever 29 is thus caused to move to the right and to operate the weft shuttle changing mechanism, and thus the weft shuttle is changed, either by dropping a shuttle box or causing a new shuttle to come into use by rotation of a rotating shuttle holder.

The operation of the device is as follows:

Assuming the mechanism to be in the position shown on the drawing, the peg 3 on the pattern link 2 is in operative position and raises the members 13, 12, 11 and 10 so that the pawl 8 is out of engagement with the ratchet 7, and therefore the auxiliary cylinder 4 is stationary. The bar 5 of the auxiliary cylinder chain being in operative position, the peg 6 thereof raises the arm 21, and therefore the members 23 and 24 are lowered causing the hook 30 of the arm 25 to engage the reciprocating griffe bar 17, and the arm 25 is carried forward about 3 inches, with the pivot of member 26, abutting against the stop 26a, acting as a fulcrum, and member 28 is moved a distance of $1\frac{1}{2}$ ". This motion causes the shuttle box to be moved in its uppermost position. On the next pick of the loom, the griffe bar 17 and hook 30 move back-

wards, and the hook 31 is caught on griffe bar 18, and carried forward a like distance, so that the lever 27 merely turns on an imaginary fulcrum at its centre, and lever 28 remains in the same position, $1\frac{1}{2}$ inches from its normal position, and lever 29 remains stationary. This continues as long as a bar 5 containing peg 6 remained under lever 21 with the lever 27 oscillating about its centre, and the shuttle box remains in its topmost position.

When the pattern bar 2a comes in operation, since there is no peg thereon, the members 13, 12, 11 and 10 drop, so that the pawl 8 engages the ratchet 7, and since this pawl has a constant reciprocating motion imparted thereto by the motion of the griffe bars, the pawl causes the auxiliary cylinder 4 to rotate and bring the bar 5a in operative position. Since the bar 5a has no peg, the arm 21 drops and raises the members 25 and 26 out of engagement with the griffe bars 17 and 18, so that the lever 29 is moved to the left either by the weight of the shuttle box or by a spring, so that the shuttle box is dropped and the weft shuttle is changed. On the next operation, the pattern link 2b comes into the operative position, and since it has the peg 3a thereon, this peg will lift the pawl operating mechanism, and the pawl will be disengaged from the ratchet, so that the cylinder 4 remains stationary. This cylinder 4 will remain stationary as long as pattern links 2, 2a, etc. having pegs are in operation, so that the same weft shuttle remains in the loom. It is only when a pattern link having no peg is in the operative position that the cylinder 4 is moved, and a new auxiliary bar 5b comes in operation, which may or may not have a peg to cause the shuttle box changing mechanism to operate.

By my device, changes in weft may be effected very simply. This change of weft may be change of color of yarn, change of nature of yarn, or merely change of shuttle to replenish the supply of the same. Thus if a mixed fabric containing mixed natural silk and yarn made of an organic derivative of cellulose such as cellulose acetate in the weft is to be made, shuttles containing these different yarns may be changed by my mechanism.

To illustrate the advantages accruing from my invention, the following instance will be given. Assuming that a striped fabric is to be woven having a pattern of 20 picks red filling, 40 picks white, 20 picks red, and 80 picks white filling. If my mechanism is not used, and supposing one link of the pattern chain is required for each two picks, a pattern chain of 80 links will be required. By the use of my invention, a pattern chain of only 8 links on the auxiliary cylinder 4, and a pattern chain of 10 links on the ordinary cylinder 1 is required. Of the ten links on

cylinder 1, nine consecutive ones have pegs 3a, 3b etc., while the tenth link is without a peg. Of the eight links of the auxiliary cylinder, the first has a peg, the next two have 5 no pegs, the fourth has a peg, while the last four have no pegs. This cylinder is turned every two picks of the loom in the normal manner, and while the links which are provided with pegs are in operative position, the cylinder 4 remains stationary with a link 10 5 having a peg therein under the lever 21, so that the same filling of red yarn is being woven. When the tenth link on cylinder 1, having no peg comes under lever 13, it causes 15 the cylinder 4 to bring link 5a having no peg therein under the lever 21, and the shuttle box is dropped, thus changing the shuttle so that a white yarn is woven as filling. This continues until the tenth link on cylinder 1 20 is again in operative position causing the auxiliary cylinder 4 to present the link 5b under the lever 21, but as this link has no peg therein, the shuttle box is not changed, and the white filling continues to weave for 25 20 picks more. The next link on cylinder 4 has a peg inserted, so that the shuttle box is raised, thus leaving the weft shuttle with the red yarn in operation for 20 picks. The next four consecutive links on cylinder 4 have 30 no pegs therein, thus the shuttle box is dropped, and the shuttle containing the white yarn is in operation for 80 picks, thus completing the repeat of the design.

It is to be understood that the foregoing 35 detailed description is given merely by way of illustration and that many variations may be made therein without departing from the spirit of my invention.

Having described my invention what I 40 claim and desire to secure by Letters Patent is:

1. In a loom having a dobby with pattern bars, pegs for actuating the mechanism for controlling the movement of the shafts of the harness, a griffe bar, and shuttle holder changing mechanism, the combination of an auxiliary cylinder having pegs thereon, a hooked arm connected with the shuttle holder changing mechanism, a lever actuated by said 45 50 pegs for causing said hooked arm to engage the griffe bar, and means, including such griffe bar, actuated by said pattern bars to cause the auxiliary cylinder to rotate.

2. In a loom having a dobby with pattern 55 bars, mechanism for controlling the movement of the shafts of the harness, a griffe bar and shuttle holder changing mechanism, the combination of an auxiliary cylinder having pegs thereon, a hooked arm connected 60 65 with the shuttle holder changing mechanism, a lever actuated by said pegs for causing said hooked arm to engage the griffe bar, pegs on said dobby pattern bars for actuating the mechanism controlling the movement of the shafts of the harness, other pegs on some of

said dobby pattern bars, reciprocating means co-operating with said griffe bar adapted to operate said auxiliary cylinder and means actuated by said last named dobby bar pegs to engage and disengage said auxiliary cylinder. 70

3. In a loom having a dobby pattern chain of bars, mechanism for controlling the movement of the shafts of the harness, a griffe bar and a shuttle holder changing mechanism, the combination of an auxiliary cylinder having a chain of bars thereon, pegs on some of said bars, a mechanism having a hook adapted to engage the griffe bar and connected to the shuttle holder changing mechanism, a lever operated by the pegs on the auxiliary cylinder bars to cause said hook to engage the griffe bar, a ratchet on said auxiliary cylinder, a reciprocating pawl connected to the griffe bar and adapted to engage said ratchet, pegs on the dobby pattern bars for actuating the mechanism controlling the movement of the shafts of the harness, other pegs on some of said dobby pattern bars, and mechanism operated by said last named pegs 80 85 90 to cause the pawl to engage or disengage said ratchet.

In testimony whereof, I have hereunto subscribed my name.
